ABSTRACT OF THE DISCLOSURE

A pattern marker for marking dots or lines on the inside or outside of material without the use of tracing paper. The marker includes a base and a pad, a pivotal hollow tube having a piece of chalk fitted in one end, a pivotal bar with a second pad, the pivotal bar is moved to press the chalk to making a mark on the material, and a pivotal bar having a locating circle for locating the marker in a desired location.

Summary of the invention

My marker comprises a vertical member with a first horizontal plate extending outward from the bottom of the member. A second plate extends over the first plate and is pivotally secured at one end to the member intermediate its ends. A third member extends over the second plate and is pivotally secured at one end to the top end of the member. A first pad is secured to the top surface of the first plate adjacent its free end. A second pad is secured to the bottom surface of the second plate adjacent its free end. An elongated element pivotally secured to said member intermediate the first and second plates extends outward therebetween with a free end essentially aligned with the pads. A piece of chalk is partially inserted into the free end of the element. The element and the second and third plates are all pivotable in the same vertical plane.

When used as described hereinafter my pattern marker can be used for marking dots or lines on the outside and/or inside of double material with the pattern still attached to the cut out material and without using tracing paper.

Brief description of the drawings

In the drawings:

FIG. 1 is a perspective view of my marker;

FIG. 2 is a view of the base back plate without attachments;

FIG. 3 shows my marker in marking position;

FIG. 4 is an end view of my marker;

FIG. 5 illustrates in detail some of the parts shown in FIGS. 1 and 3;

FIG. 6 is a view of container for chalk holder;

FIG. 7 shows the chalk holder in a closed position;

FIG. 8 shows the part of FIG. 7 in partially open position;

FIG. 9 is a detail view similar to FIG. 8;

FIG. 10 is a cut away view of the parts of FIG. 5;

FIGS. 11A and 11B are further detail views of the plate of FIG. 2;

FIG. 12 shows one of the parts used in FIGS. 11A and 11B;

FIG. 13 is a view of an airfoam pad used in my marker; and

FIG. 14 is a cut away end view illustrating the marking action.

My marker has a light weight, ridged metal, narrow flat base 15, with an airfoam pad 16 on top at this narrow end of base 15. FIG. 1, on base 15 still flat but wider is 17. About $\frac{1}{10}$ of the distance from the beginning is a back plate 18, with $\frac{1}{10}$ of the wider base 19 running past plate 18. FIG. 4.

The back plate 18 has an opening 20 through the center

2

of the lower part of plate 18, FIG. 2, on the front of the back plate 18 along both vertical sides of opening 20, from the top of the back plate 18, to the base 17, are 2 front braces 21 and 22, a separate cover 23 and 24 is over the top of braces 21 to 22, covers 23 and 24 extend to each side of plate 18 and to be even with outer edge area of base 17 FIG. 2, a rim drops down along the edge of outer sides of the covers 23 and 24, starting from the back plate 18 and around to the front braces 21 and 22 FIG. 2.

Above the opening in plate 18, between the braces 21 and 22 is a ridged flat bar 27, attached to a pin 28a, pin 28a is attached to each side of the front braces 21 and 22, in holes 29a, FIG. 2 and FIG. 3, the pin 28a acts as a hinge and lets bar 27 swing up and down, bar 27 is as wide as the space between the front braces 21 and 22, narrows down until it is as narrow as the beginning of base 15, and as long as base 15, bar 27 has an airfoam pad 30, on the bottom side, directly in line with pad 16, FIG. 1 and FIG. 3. Airfoam pads are of 2 parts, 16a base and 30a base having higher sides, and foam pad 16b and 30b which have smooth covering are anchored to base 30a-16a, FIG. 13.

Above bar 27 attached to be level with the top of back plate 18, is an identical bar 31 FIG. 1 and FIG. 3, but is made of clear plastic, does not have a pad, is slightly longer than lower bar 27 and base 15, is the same width from one end to the other as the space between the front braces 21 and 22, has an upward curve 32, on the end over pads 16 and 30 FIG. 1 and FIG. 3, in the center of bar 31 near the curved end 32 is a printed round black circle 33, with an X 34, marked in the center of circle 33, and short lines 35 following in the center of bar 31 towards the hinged area FIGS. 1 and 3.

A rectangular block 36 which has 2 pins 37a and 37b in the center, one opposite of the other FIG. 5 slips through the back of plate 18 through opening 20, and on between the braces 21 and 22 until even with the front part, of braces 21 and 22, and the 2 center pins 37a and 37b touch the back of plate 18 FIG. 3 and FIG. 4, pins 37a and 37b are in a horizontal position, one on each side of opening 20 in the back of plate 18, said pins are anchored to back plate 18 with braces 38a and 38b, braces 38a and 38b are fitted so that pins 37a and 37b are free to turn inside of said braces, pins 37a and 37b anchored this way let rectangular block 36 tilt up or down FIG. 4, the other $\frac{1}{2}$ of the rectangular block 36 is left protruding in the back of plate 18, FIG. 4.

The hollow tube 39 is fitted through the center of the rectangular block 36, FIG. 3, the tube 39 has a flange 40 which fits in groove 41, groove being on the inside of the rectangular block 36 FIG. 5, FIG. 6, FIG. 10. The tube 39 fitted in this way cannot slide back and forth, but will turn inside of the rectangular block 36, tube 39 extends over base 19 in back of plate 18 and has a round knob 42 at this end FIG. 1, FIG. 3, and FIG. 4, a chalk holder 43, FIG. 7, screws into the other end of tube 39 which extends in front of braces 21 and 22. FIG. 1 and FIG. 3, chalk holder 43 extends from this tube 39 to the edge of airfoam pads 16 and 30, FIG. 3, chalk holder 43 is cut open lengthwise FIG. 8, the end of chalk holder 43 which extends to the airfoam pads, 16 and 30, is lined with airfoam FIG. 8, the other end which screws into 39a has threads 43a and a flange 43b, the threads 43a fit into threads 39a, flange 43b keeps chalk holder 43 from screwing any further than this flange 43b into threads 39a so as not to shorten chalk holder 43 which must be at the edge of pads 16 and 30, this same end has a hinge 45 FIGS. 8 and 9, the hinge 45 keeps the 2 pieces of the chalk holder 43 together and lets chalk holder open and close FIG. 7 and FIG. 8, the hinge 45 has a pin spring 46 with its loop over pin 47 of hinge 45, the 2 ends 48 of

spring 46 are anchored, one to each half of chalk holder 43 FIG. 9, this spring 46 opens chalk holder 43 when said holder is unscrewed from tube 39, a piece of chalk 49' is placed in $\frac{1}{2}$ of chalk holder 43, with part of chalk 49' left protruding out, FIG. 7 and FIG. 8, both pieces of chalk holder 43 are pressed together, chalk holder 43 is screwed back into hollow tube 39, this keeps chalk holder 43 closed, which causes airfoam lining 44 to press against chalk 49' holding chalk 49' firmly to keep it from slipping, also cushions it to keep it from breaking.

A side plate 49 is fitted in each corner on the outer sides of the front braces 21 and 22 FIG. 11A, side plate 49 has 2 prongs 50 and a lower wedge 49a, with a tension spring 52 out of the way of the prongs 50 FIG. 12, prongs 50 of side plate 49 rest in holes 51, holes being in the front braces 21 and 22, wedge 49a extends in front of braces 21 and 22. To keep side plates 49 in place is a rim 53 on the base 17 area, starting from the back plate 18 around to the front of braces 21 and 22, and rims 25 and 26 FIG. 2. When both side plates 49 are pressed at the same time, plate 49 pushes prongs 50 through holes 51 and under bars 27 and 31, wedges 49a under tube 39, raising all three at one time—FIG. 11B and FIG. 1—when pressure is released on side plates 49, tension spring 52 pushes side plates 49 back against rims 53 and rims 25 and 26, FIG. 11a. FIG. 3 shows bars 27 and 31 and chalk holder 43 back in starting position.

After taking out a few pins out of material and pattern along the area of the pattern where the marks are to be transferred to the material, using one hand, with fingers on one side of the back plate 18 and thumb on the other side, the side plates are pressed to raise chalk holder and tube 39 and bars 27 and 31. These are raised for easy placement of marker and to keep marker from marking while placing in correct location. Place marker underneath of double material and pattern, with the other hand, raise 1 layer of material over chalk marker 43, raise pattern over bar 27, holding marker with side plates 49 still pressed in, place other hand above area to be marked to steady pattern. With a slight back-and-forth motion, with base of marker on flat surface, push marker until marks to be marked are seen in the center of the circle 33 of bar 31. The hand on the pattern is moved up and the thumb and forefinger is cupped around bar 31, side of palm is resting on pattern. Fingers and thumb steady marker while side palm of hand steadies pattern, the other hand releases side plates 49 which puts marker in position for marking, turn knob 42 for marking dots, or marker is held by back plate 18 only and pulled back to mark lines, the fingers and thumb cupped around bar 31 steady marker but let it slide through thumb and forefinger when pulling marker for marking lines.

The weight of bar 27 pushes pad 16 against chalk 49', chalk 49' pushes against pad 31 causing equally dividing of material for perfectly matched markers. If marker is used with a hard base and no pad on the bar 27 top material is raised over the chalk and causes mismatched marking. Any side of the material may be marked by placing chalk 49' on the side to be marked. For both sides of double material to be marked at one time, marker

is placed between the double material. FIG. 1 shows both sides marked at one time. FIG. 3 shows top side of material being marked. Pattern is always between bar 31 and bar 37. Different colors of chalk may be used of black-board type chalk but the chalk is only $\frac{1}{8}$ " in diameter.

General design of individual parts of the invention may be changed in regard to manufacture and production. However, in general it is necessary to use (1) airfoam pads for perfectly matched marks, (2) an airfoam lined, cut lengthwise and hinged chalk holder with thin chalk and airfoam lining for the purpose of holding chalk firmly and to cushion against breakage, (3) a weight bar pushing material against chalk or chalk against material, (4) a line-up bar, to see dots and lines of the pattern through the top of the bar, (5) side plates to raise chalk marker holder and both bars at the same time.

Having thus described my invention, I claim as new and desire to secure by Letters Patent:

1. A marker comprising
a vertical member;
a first horizontal plate extending outward from the bottom of said member;
a second plate extending over the first plate and pivotally secured at one end to said member intermediate the ends of the member;
a third plate extending over the second plate and pivotally secured at one end to the top of said member;
an elongated element extending outward from said member between said first and second plates with one end being essentially aligned with the free ends of the plates, said element being pivotally secured to said member; and
chalk means disposed in said one end of said element.
2. A marker as set forth in claim 1 wherein said third plate has a viewing insert disposed in the free end thereof.
3. A marker as set forth in claim 2 wherein a first pad is secured to the top surface of the first plate adjacent its free end and a second pad is secured to the bottom surface of the second plate adjacent its free end.
4. A marker as set forth in claim 3 wherein the second and third plates and the element are each pivotable in a common vertical plane.
5. A marker as set forth in claim 4 wherein said member has a transverse bore through which said element extends, said element having a recess in which a piece of chalk is disposed and manually operable plunger means to push said chalk further out of said one element end as the chalk is used up.
